LOCOMOTIVE SPARK ELIMINATOR

Henry H. Urbach and Harry A. Bell, Lincoln, Nebr., assignors of one-third to Wilson Engineering Corporation, a corporation of Delaware

Application July 16, 1932. Serial No. 622,896

5 Claims. (Cl. 230—97)

This invention pertains to apparatus for facilitating the cooling of cinders or sparks issuing from locomotives into and through their smokestacks.

5 With certain grades of coal a strong tendency exists for large and red-hot cinders to be carried through the boiler tubes and expelled from the smokestacks of the locomotives whence they may then fall to the ground so red-hot as to cause roadside fires. To avoid this evil it has been proposed heretofore to deflect as many of the live sparks as possible, to collect them in the front end of the boilers and thereafter discharge them from time to time whenever they 10 have accumulated in large quantities. Such systems often are unsatisfactory due to clogging of the front ends of the boiler shells and tend to 15 impede the proper draft of the locomotive.

Another expedient that has been attempted is 20 to cause the pulverizing of the cinders so that they may not have sufficient mass after emerging from the smokestack to retain enough heat to be the cause of roadside fires. However, such systems also have their disadvantages, one of 25 them being that whenever excessive pulverization occurs the very fine dust produced thereby finds its way into the coaches and sleeping cars of the trains and increases the difficulty and expense in keeping such coaches and cars suitable 30 for service. Another disadvantage connected with the pulverizing of the cinders lies in the fact that the cinders cause rapid wear on the metal parts which produce their pulverization, hence such equipment oftentimes needs to be 35 replaced after short periods of use.

This invention aims to make it possible to cool the cinders sufficiently before they emerge from the stack so that they may not occasion roadside fires and yet without pulverizing the cinders.

40 Thus in accordance with this invention it is an object to procure sufficient cooling of the cinders without causing any serious wear on the parts required to produce this cooling effect. Other objects and advantages of this invention 45 will be more readily understood from a perusal of this specification.

In the drawing:

Fig. 1 is a central vertical sectional view of a 50 boiler equipped in accordance with this invention, and

Fig. 2 is a plan section taken on line 2—2 of Fig. 1.

Referring now to the drawing, the front end 55 of the boiler forwardly of the tube sheet 1 consists generally of the front barrel portion 2 hav-

ing an outer stack 3 and an inner stack 4 for the exhaust of the products of combustion. The usual steam jet 5 mounted directly below the stack is of course connected to receive the exhaust from the cylinders, but the connection is not herewith shown as it is too well known in this art to require description. The steam jet extends upwardly through a horizontal plate 6 which extends across the bottom of the barrel and is joined thereto at the lines 7 and 8 shown in Fig. 2. A vertically extended wall generally indicated as 9 having a rearwardly bent portion 10 to accommodate the curvature of the nearby smokestack and its apron 11 prevents the products of combustion issuing from the boiler tubes 12 and 13 from flowing forwardly in any direction excepting downwardly beneath the horizontal plate 6.

The gases thus deflected by the vertical wall 9 and the horizontal plate 6 must flow to the forward end of the boiler shell and thence are induced to flow upwardly through the curved passage 14 until they emerge through the aperture at the rearward end of said passage in proximity to the inner stack 4.

In the preferred embodiment this passage is formed between two walls 15 and 16 which extend generally parallel to each other transversely to the longitudinal axis of the boiler and between two vertical walls 17 and 18 which enclose the 85 sides of the passage. As the curved passage progresses upwardly and rearwardly of the stack, we prefer to have one of its side walls depart from the plane of the wall 18 and be curved as is the wall 19 inwardly toward the stack, so that the 90 gases which emerge from the aperture near the stack between the curved vertical wall 19 and the extremities of the top walls 15 and 16 may be given a rolling swirling motion and cast downwardly about the stack upon the top of the plate 95 6 and into the semi-cylindrical space formed on the surface of the wall 15, from which spaces the gases then may emerge through the stack under the inspiriting action of the exhaust steam jet 5.

Above the passage 14 a vertical wall 21 extends 100 across the top of the front end boiler shell to prevent escape of gases through that locality toward the stack. Likewise at the lateral sides of the passage 14 between the walls 17 and 18 and the periphery of the boiler shell vertical walls 22 and 105 23 likewise are provided, these latter walls cooperating with the partition 21 to prevent any gases which may not enter the passage 14 but may surround it from finding their way into the stack. While some gases may thus escape up into the 110

space above referred to, these gases will merely eddy around in the space, cool and intermingle to some extent with fresher gases entering the passage 14, thus contributing to the cooling of the cinders as is desired.

We have found that any cinders which tend to fall directly below the entrance of the passage 14 will be swept up by the escaping gases and discharged through the passage 14 and stack 4. Hence no harmful accumulation of the cinders occurs in a locomotive equipped in accordance with this invention.

We have found that the long tortuous passage herein provided gives ample time for the cinders to be cooled sufficiently so that after emerging from the stack they will not cause roadside fires. However, in their travel through these passages the swirling motion imparted to them is not of a character which causes the cinders to grind on the walls and become to any considerable extent pulverized. Thus no harmful amount of dust is produced.

While the curved wall 19 is preferred for the rather corkscrew motion it imparts to the gases flowing from the passage 14, yet in some cases it may be omitted if desired and the side walls of the passage 14 made parallel from end to end.

The upstanding collar 24 which surrounds the outlet of the steam jet is provided for the purpose of discouraging cinders from sliding from the top of the plate 6 into the steam jet whenever the engine is coasting. However, due to the violent eddying of the gases after they emerge from the passage 14, cinders will not accumulate to any considerable extent in the space around the stack, although there may be a few stray cinders lying about.

To permit installation of this equipment it is not necessary to change existing nozzle stands or stack locations. The smoke box itself requires no altering. There is no interference with other accessories such as the feed water heater, the superheater header, front end throttle, etc. Wherever this invention is installed the whole front end can be inspected without removal of any parts.

Having shown and described this invention, we claim:

1. In combination with a locomotive, walls positioned in the front end of the boiler arranged for deflecting gases issuing from the boiler tubes past and out of communication with the exhaust steam jet and smokestack forwardly thereof, and additional walls constructed to provide a smooth curved passage for conducting said gases from a point forwardly of the stack thence upwardly above the space between the outlet of the exhaust

steam jet and the smokestack thence downwardly into said space.

2. In combination with a locomotive, means for guiding and conducting gases issuing from the boiler tubes past and forwardly of and out of communication with the exhaust steam jet and the smokestack, and means for receiving said gases forwardly of the stack and for conducting them upwardly well above the bottom of the stack thence rearwardly and downwardly into proximity and in communication with the bottom open end of the stack above the steam jet.

3. In combination with a locomotive, walls forming a baffle for obstructing direct communication between the exit ends of the locomotive flues and the space between the exhaust steam jet and the bottom of the locomotive stack, and imperforate walls connected with the first said walls provided for guiding the gases and for leading them forwardly to the front end of the locomotive beyond the stack thence curving rearwardly and upwardly above the bottom of the stack and thence downwardly into the space between the bottom of the stack and the top of the exhaust steam jet.

4. In combination with a locomotive, baffling means between the exit ends of the boiler flues and the space between the bottom end of the stack and the top of the exhaust steam jet for deflecting the flue gases downwardly and forwardly past the steam jet, and imperforate baffling walls for conducting the flue gases upwardly, thence rearwardly higher than the bottom of the stack and returning them downwardly surrounding the stack toward its lower open end into the space between said open end and the top of the steam jet.

5. In combination with a locomotive, an upright wall between the exit ends of the flue and the smokestack and exhaust steam jet terminating lower than the top of the steam jet but above the bottom of the boiler shell, a horizontal wall extending from the bottom of the first said wall forwardly past said steam jet, and walls free from irregular obstructions constructed to provide a smooth curving flue passage upwardly from the forward bottom portion of the boiler shell and rearwardly to a region higher than the bottom of the stack and above said horizontal wall, said walls cooperating to deliver the flue gases from said passage into an enlarged space forwardly of the upright wall and subject to the ejecting action of said steam jet.
